US00D679758S

(12) United States Design Patent
Matt

(10) Patent No.: US D679,758 S
(45) Date of Patent: * Apr. 9, 2013

(54) CARD

(75) Inventor: Michael Matt, Phoenix, AZ (US)

(73) Assignee: Chips Unlimited, Inc., Tempe, AZ (US)

() Term: 14 Years

(21) Appl. No.: 29/422,253

(22) Filed: May 17, 2012

(51) LOC (9) Cl. 20-02

(52) U.S. Cl. D20/40

(58) Field of Classification Search D20/10, D20/19, 22-28, 40, 99; 40/124.01-124.09, 40/124.11-124.19, 124.191, 299.01, 310, 40/312, 360, 625, 642.01; D19/1, 9, 10; 283/56, 71, 81

See application file for complete search history.

(57) CLAIM

The ornamental design for the card, as shown and described.

DESCRIPTION

FIG. 1 illustrates a card showing an embodiment of my new design;

FIG. 2 illustrates the opposite side of the card of FIG. 1; FIG. 3 illustrates a card showing an alternate embodiment of my new design including environmental features; and, FIG. 4 illustrates the opposite side of the card of FIG. 3. In the drawings, the broken lines illustrate environment and form no part of the claimed design.

1 Claim, 4 Drawing Sheets
